UNITED STATES PATENT OFFICE

CHARLES EDWIN NELSON, OF CHICAGO, ILLINOIS, ASSIGNOR TO WESTERN ELECTRIC COMPANY, INCORPORATED, OF NEW YORK, N. Y., A CORPORATION OF NEW YORK

MATERIAL FORMING APPARATUS

Application filed October 9, 1928. Serial No. 311,284.

This invention relates to improvements in material forming apparatus, and more particularly to improvements in apparatus for forming articles from metal blanks.

5 The principal object of the invention is the provision of an improved apparatus of simple and inexpensive construction for efficiently and expeditiously forming metal blanks into articles of various predetermined 10 shapes.

In accordance with the general features of the invention, there is provided in one embodiment thereof a material forming apparatus including a dial or disk having a 15 face complementary to the periphery of a forming roll and provided with recesses for conveying metal blanks from a magazine into contact with the forming roll. Discharge or 20 ejection of the formed article or part is effected automatically as the disk conveys them away from the forming roll.

Other features and advantages of the invention will become apparent from the following detailed description of one embodiment thereof, reference being had to the accompanying drawings, wherein

25 Fig. 1 is a plan view, partly broken away, of an apparatus embodying the features of the invention;

30 Fig. 2 is a vertical section thereof taken on line 2-2 of Fig. 1;

Fig. 3 is an enlarged view of the blank discharging means, taken on line 3-3 of Fig. 1, and

35 Fig. 4 is an enlarged fragmentary view of the portion of the disk in contact with the forming roll.

Referring now to the drawings in detail in which like numerals designate similar parts in the several views, there is disclosed a horizontally disposed base 10 having a vertically extending portion 11. In the horizontal portion 10 is journaled a vertical shaft 12 on which is secured a horizontally 40 disposed dial or disk 13, the top surface of which cooperates with a forming roll 14 mounted on a horizontal shaft 15 journaled within the vertical portion or support 11. The top surface of the dial or disk 13 is complementary to the periphery of the forming

roll 14 which has suitable depressions and elevations to compress material into a predetermined shape. Recesses 18 provided at spaced points in the top surface of the dial 13 convey metal blanks 19 from a chute or 55 magazine 20 into contact with the periphery of the forming roll 14.

As the dial or disk 13 conveys the formed metal blanks 19 away from the forming roll a stationary ejecting member or obstruction 60 27 contacts the ends of the blanks 19 projecting from the dial 13 and causes the blanks to be thrown out of the recesses 18 into a suitable receptacle (not shown) located adjacent to the ejecting member. 65

The recesses 18 are most expeditiously constructed by milling the top surface of the dial 13 into the shape which the formed blank of metal is to be depressed by the roll 14, and then securing spaced plates 23 thereto by means of screws 24. The spaces between the plates provide the necessary recesses. A vertical section of one form of a recess so constructed is shown at 25 beneath the magazine 20, Fig. 2. In order that the plates 23 will successively pass under the forming roll 10, it is, of course, necessary that the top surfaces thereof comply with and be complementary to the periphery of the forming roll 14. The thickness of the plates 23 70 must be greater than the extent of the greatest irregularity on the periphery of the forming roll 14 in order that the plates may be milled down to conform to the periphery of the roll, as shown in Figs. 2 and 4. As shown 75 in Fig. 4, the metal blank 19 being formed by the roll 14 preferably projects slightly above the top surface of the plates 23 so that it may be formed by the roll without the roll having to contact the plates. 80

The magazine 20 consists of an upright rectangular box or chute into the top of which the metal blanks 19 are passed in stacked form, and from the bottom of which the blanks successively gravitate as the recesses 18 pass thereunder. The recesses 18 are of just sufficient depth to receive a single blank, and while the plates 23 are passing beneath the magazine no blanks are conveyed therefrom, but the top of the plate 23 con- 85 90 95 100

tacts with the undersurface of the next succeeding blank, holding it against descent. The sides of the magazine extend down to a point which almost contacts with the plates, thereby preventing the subsequent blank from being conveyed by the dial or disk 13 until a recess approaches. In order that the dial 13 may rotate at a high rate of speed, the recesses 18 are made substantially wider than the metal blanks 19 so that the blanks have sufficient time to gravitate thereinto. A force may be applied to the top of the stack of blanks to accelerate this action.

The stationary ejecting member 27 consists of an L-shaped plate, as shown in Fig. 3, secured to the base 10 and having a suitably shaped surface 28 for contacting a projecting end of the formed metal blank as it is rotated. Continued rotation of the blank after it is in contact with the ejecting member causes the blank to be tipped free of the recess 18 and to be thrown out from the rotating dial into a receptacle located below the ejecting member.

25. Thus, there is provided by this invention as aforescribed a material forming apparatus which is simple in construction and which operates to expeditiously shape material into a great number of possible forms.

30. The invention is of course not to be limited to the embodiment as here described, but is capable of various modifications without departing from the scope and spirit of the appended claims.

35. What is claimed is:

1. In a material forming apparatus, a magazine for retaining material, a roll for forming the material, and a disk for conveying the material from the magazine to the roll and for forming the material.

2. In a material forming apparatus, a magazine for retaining material, a forming disk for removing the material from the magazine and for supporting it, and a roll for compressing the material against the disk and forming the material while supported thereon.

3. In a material forming apparatus, a magazine for retaining material, a disk provided with a receptacle of a predetermined shape for removing the material from the magazine and for supporting it, and a forming roll having a periphery of a predetermined form and cooperating with the disk for forming the material while supported in the recess of the disk.

4. In a material forming apparatus, a magazine for retaining metal blanks, a dial provided with recesses of predetermined shape for removing the blanks from the magazine and for supporting the blanks, and a forming roll having a periphery of a predetermined form for pressing the blanks into the recesses and thus forming the blanks while supported by the disk.

5. In a material forming apparatus, a magazine for retaining metal blanks in stacked form, a dial rotatable thereunder and containing recesses into which the metal blanks successively gravitate, a roll being in close juxtaposition to the dial and cooperating therewith for forming the blanks, and means for ejecting the formed blanks from the dial following their formation by the roll.

6. In a blank forming apparatus, a rotatable dial having a succession of radial recesses of predetermined contour constructed within its upper surface, a magazine for successively depositing blanks to be formed into the recesses, a forming roll mounted above the dial for successively pressing the blanks into the recesses and forming them, and means for successively ejecting the blanks from the dial recesses as they are formed.

7. In a blank forming apparatus, a magazine for retaining blanks, a dial having radial recesses conforming to the shape of the blanks to be formed into which said blanks are deposited from said magazine when in alignment therewith, means for moving said dial to convey successively away from said magazine the blanks deposited in said recesses, and a forming roll which forms the blanks carried in said recesses.

In witness whereof, I hereunto subscribe my name this 29th day of September A. D., 1928.

CHARLES EDWIN NELSON.
